(57) **CLAIM**

The ornamental design for a box for confectionary articles, as shown and described.

DESCRIPTION

FIG. 1 is a perspective view of a box for confectionary articles in accordance with my new design;

FIG. 2 is a top plan view of the box of FIG. 1;

FIG. 3 is a bottom view thereof;

FIG. 4 is a front elevational view thereof, the rear elevational view being identical; and

FIG. 5 is a right side elevational view thereof, the left side elevational view being identical;

FIG. 6 is a perspective view of the box of FIG. 1 but showing an inner article tray partially removed;

FIG. 7 is a perspective view of the inner article tray removed from the box; and,

FIG. 8 is a top plan view of the article tray of FIG. 7.

The contents of the box for confectionary articles shown in broken lines in FIGS. 1, 2, 6 and 7, form no part of the claimed design.
